UNITED STATES PATENT OFFICE

101,134

DESIGN FOR A ROAD MARKER

Charles L. Moorman, Blue Island, Ill.

Application July 25, 1936, Serial No. 64,050

Term of patent 14 years

To all whom it may concern:

Be it known that I, Charles L. Moorman, a citizen of the United States and a resident of Blue Island, in the county of Cook and State of Illinois, have invented a new, original, and ornamental Design for a Road Marker, of which the following is a specification, reference being had to the accompanying drawing forming a part thereof, and in which:

Fig. 1 is a top plan view of a road marker showing my new design; and

Figs. 2, 3 and 4 are side views of the same.

I claim:

The ornamental design for a road marker, as shown.

CHARLES L. MOORMAN.
